UNITED STATES PATENT OFFICE.

DANIEL M. SECHLER, OF CINCINNATI, OHIO.

TWO-WHEELED VEHICLE.

SPECIFICATION forming part of Letters Patent No. 324,886, dated August 25, 1885.

Application filed June 4, 1885. (No model.)

To all whom it may concern:

Be it known that I, DANIEL M. SECHLER, a citizen of the United States, residing at Cincinnati, in the county of Hamilton and State 5 of Ohio, have invented certain new and useful Improvements in Two-Wheeled Vehicles, of which the following is a specification, reference being had therein to the accompanying drawings.

10 The object of the first part of my invention is to attach the thills of a two-wheeled vehicle to the body thereof in such manner as to relieve the latter of the disagreeable vertical vibrations incidental to the motions of the 15 horse. To accomplish this result I mount the vehicle on any approved form of riding spring or springs and support the front portion of the body on a rod or bar, which I have designated as the "pivot-shaft," because it serves as the 20 fulcrum or center of motion for the thills. The opposite ends of this pivot-shaft are immovably fastened either to the thills or equivalent draft members, and suitable necks or 25 journals are formed on said shaft near the thills, which necks are adapted to rock within bearings secured to the body of the vehicle. Applied to this shaft at or near its mid-length is one end of a spring, whose other end is securely fastened to the vehicle body, the object of this spring being to permit the pivot- 30 shaft to rock in either direction within its bearings after the tension of said spring has been overcome. The aforesaid spring is confined within a housing attached to the front wall of 35 the well or pit of the body, the free end of the spring being inserted in a slotted hub or boss, through which latter is passed the pivot-shaft previously alluded to. Furthermore, this hub 40 is keyed or otherwise fastened to the pivot-shaft, so as to rock therewith, as hereinafter more fully described.

The second part of my invention comprises a peculiar construction of keeper that limits both vertical and lateral or horizontal play of the rear ends of the thills, and also prevents 45 said thills being disengaged from the vehicle in case the pivot-shaft should break. This keeper consists of a plate or frame projecting from the side of the body, which plate is 50 slotted vertically to permit the passage of a bolt, the latter being tapped into the rear end of the thill and being free to traverse said

slot. It is preferred to surround a portion of this bolt with an india-rubber bushing to prevent rattling within said slot, as hereinafter 55 more fully described.

The third part of my invention comprises a recessed and flanged box, which is attached to the thills and carries one end of the pivot-shaft, the flange serving to prevent "end-play" 60 of the latter, as hereinafter more fully described.

In the annexed drawings, Figure 1 is a side elevation of the front portion of a two wheeled vehicle embodying my invention. Fig. 2 is a 65 plan of the under side of the same. Fig. 3 is an enlarged longitudinal section of the pivot-shaft and its accessories. Fig. 4 is an enlarged vertical section of the housing that contains the pivot-shaft spring. Fig. 5 is an 70 enlarged side elevation of one of the boxes wherewith the pivot-shaft is immovably fastened to the thills. Fig. 6 is a perspective view of the flanged cap of said box. Fig. 7 is a 75 modification of the invention. Fig. 8 is a horizontal section of the shaft-keeper and its accessories. Fig. 9 is a front elevation of said keeper.

A represents the front part of a two wheeled vehicle, which may be mounted on any approved form of riding-springs, portions of the latter being seen at B B'.

C represents the customary well or pit of the body, the front wall, c, of the same having attached to it a housing composed of a fixed 85 member, D, and a detachable cap, E, which members D E may be secured with bolts F or otherwise. This housing D E affords a bearing for cylindrical collars G G', projecting from the opposite ends of a hub or boss, H, 90 the latter having a slotted or forked extension, I, within which plays the free end of a short plate-spring, J, composed of one, two, or more leaves, as circumstances may suggest. The fixed end of this spring is clamped between the members D E of the housing, and said members are chambered out at d e, respectively, to permit sufficient play of the free end of said spring. Passing completely through this hub H and its collar G G', and 95 rigidly fastened therein, is the "pivot-shaft" K, previously referred to. This shaft may be of any suitable shape; but practical experience has demonstrated that a square bar of 100

iron or steel can be more conveniently used than any other form. Said shaft is accordingly shown as being square in transverse section, thereby avoiding the use of pins, keys, 5 or other retaining devices for fastening it to the hub H G G'. Cylindrical necks $k k'$ are made near the opposite ends of the shaft, as seen in Fig. 3, which necks are journaled in bearings L L', depending from the side 10 sills or frame of the body, said shaft being carried out beyond these bearings to connect with the thills N N' of the vehicle. This connection may be made in any manner that will permit the shaft K to rock with every vertical 15 vibration of the thills N N', or, in other words, the aforesaid shaft must serve as the pivot, fulcrum, or center of motion of said thills. Therefore, as the pivot shaft is square, I make a right-angled recess, o, in a strap, O, 20 secured to the under side of the thill, as seen in Fig. 5, which recess is equal to half the depth of said shaft. P is a cap similarly recessed at p, and adapted to be retained against the under side of strap O by bolts R. 25 S is a flange projecting upwardly from the outer end of the recess p, so as to serve as a stop that prevents the shaft K working out of the box O o P p; but the stop S' (seen in Fig. 3) closes the outer end of the recess o, it 30 being understood that the boxes of the two thills are precisely alike, and that the extreme rear ends of the latter have tapped into them bolts n n', that traverse slots t of keepers T T', which latter are provided with flanges 35 or ears to permit their secure attachment to the body A.

It is preferred to surround a portion of the bolts n n' with an india-rubber bushing, W, as seen in Fig. 10.

40 From this description it is apparent that the bolts n n' have sufficient vertical play within the slots t to allow for any necessary vibration of the rear end of the thills, while at the same time said slots prevent lateral play or spreading of these draft members N N'. Another advantage incidental to this arrangement of slotted plates and bolts is that said devices serve as keepers which prevent the thills being detached from the 45 vehicle in case the pivot-shaft K should break or the bearing L L work loose from the body A. In this event, the bolts n n' would still afford a secure hold on the plates T T'. It is also apparent that any raising or 50 lowering of the front ends of the thills N N'

will cause the pivot shaft K to rock in the bearings L L', because said shaft is rigidly attached to said thills; but the very moment the shaft begins to rock in either direction it is resisted by the spring J, on account of the 55 free end of the latter being inserted in the slotted hub that turns with said shaft. Consequently this spring serves as an equalizing device that receives and takes up the vibrations of the thills, and thereby prevents the "horse motion" being transmitted to the vehicle-body.

The invention may be modified by using two separate and distinct pivot-shafts, one for each thill, and causing the inner ends of said 70 shafts to abut within the hub H, as indicated by the dotted line in Fig. 3, by which arrangement a single equalizing-spring would be sufficient for both of said shafts; but in Fig. 7 two disconnected pivot-shafts, K' K'', are 75 shown, and each shaft is furnished with an independent housing that contains a separate spring for said shafts.

I claim as my invention—

1. A two-wheeled vehicle supported in front 80 upon a transverse pivot-shaft, K k k', and bearings L L', the opposite extremities of said shaft being rigidly attached to the thills N N', and a forked hub, G G' H I, being applied at or near the mid-length of said shaft, which 85 fork I receives the free end of a spring, J, whose fixed end is secured in a housing, D d E e, fastened to the vehicle-body, and serving as a bearing for the hub G G' H I, substantially as herein described. 90

2. A pivot-shaft bearing consisting of the recessed strap O o, recessed cap P p, and flange S, arranged to serve as a stop that prevents end shifting of the shaft, substantially as herein described. 95

3. The bolts n n', tapped into the rear ends of thills N N', and traversing the vertical slots t of keepers T T', which latter are rigidly attached to the opposite sides of the body, for the purpose specified. 100

4. The pivot-shaft K, inserted in the hub H G G', whose collars G G' are journaled in the housing D E, as herein described.

In testimony whereof I affix my signature in presence of two witnesses.

DANIEL M. SECHLER.
